(57) **CLAIM**

The ornamental design for a combined drying rack and bottle brush therefore, as shown and described.

DESCRIPTION

FIG. 1 is a front elevational view of a combined drying rack and bottle brush therefore showing our new design;

FIG. 2 is a top plan view thereof;

FIG. 3 is a perspective view thereof; and,

FIG. 4 is an exploded view of the combined drying rack and bottle brush therefore, showing the base plate, drying rack receptacles and bottle brush separately for clarity of disclosure.
